CASING HEAD VALVE

James H. Howard, Houston, Tex., assignor to J. H. McEvoy & Company, Houston, Tex., a corporation of Texas

Application March 24, 1931. Serial No. 524,791

6 Claims. (Cl. 166—15)

This invention relates generally to deep well apparatus and specifically to casing head valves.

Conventional drilling equipment includes a master gate valve in the casing and a casing head 5 on the casing above the valve. The valve is used to close the casing when the drill stem is withdrawn for repairs or other purposes. The valve cannot be closed when the drill stem is in the casing. If during drilling operations, the drill 10 encounters fluid under high pressure, what is known as a blow out often occurs; that is, fluid rushes upwardly between the casing and the drill stem; and the drill stem may be blown out of the casing. This is now prevented by a device 15 called a blow out preventer which engages the drill stem and is received and retained by the casing head.

This invention has for its principal general object the provision of a new and improved 20 casing head valve adapted to serve both as a master gate valve, and as a casing head.

A specific object of the invention is to provide a casing head valve and associated parts so constructed that a drill stem may be divided at a 25 point adjacent thereto, after which the valve may be closed to prevent a blow out.

Other objects will hereinafter appear.

Two preferred embodiments of the invention are illustrated by the accompanying drawings, of 30 which Fig. 1 is a fragmentary, partly sectional side elevation of one embodiment of the valve combined with conventional elements; Fig. 2, a detail view of the dog actuating device; Fig. 3, a horizontal section on the line 3—3 of Fig. 1; Fig. 4, a view similar to Fig. 1 of another embodiment; and Fig. 5, a horizontal section on the line 5—5 of Fig. 4.

Referring to Figs. 1, 2 and 3, the valve body is indicated at 1. It is connected at its lower end 40 by threads 2 to the upper end of casing 3.

In the lower portion of the valve body are branch passageways 4 through which muddy water, or slush, pumped through the drill stem 5 and rising upwardly in the annular space between the drill stem 5 and the casing 3, may be conveyed back to the pumps, not shown. When a blow out occurs, muddy water may be pumped through these branch passageways downwardly in the space between the casing and the drill 50 stem.

The valve or gate 6 is movable by the hand wheel 7 transversely across the main fluid passageway in the valve body to engage the valve seat 8. Such transverse movement of the valve 55 6 by the hand wheel 7 is effected by the rotatable

but longitudinally immovable stem 9 which is threaded in the valve as indicated at 10 in Fig. 4.

The opening 11 in the upper end of the valve body is much larger than is the opening 12 in the lower end of the valve body. Intermediate 60 these openings is a downwardly tapered seat 13. The internal diameter of the upper extremity of this seat is substantially equal to the diameter of the upper opening 11; and the internal diameter of the lower portion of this seat is substantially equal to the diameter of the opening 12. 65

The opening 11 is made large to permit the blow out preventer 14 to be moved into the fluid passageway of the body and upon the seat 13 below the valve 6. This blow out preventer is 70 described and claimed in my pending application for Letters Patent of the United States, Serial No. 432,050, filed February 28, 1930. As shown in Figs. 1, 2 and 3, it is substantially 75 frusto-conical and comprises a pair of sections 15 and 16, hinged as indicated at 17 so that they may be placed around the drill stem 5. The sections are held together by the latch 18. Between the upper and lower metallic rings 19 and 20 is a rubber ring 21. The upper ring 19 is 80 adapted to be held in place by dogs 22, yieldably 85 held in their active positions by springs 23; and movable into their inactive positions by any suitable device such as the tool 24 (Fig. 2) comprising a cylindrical head adapted to be rotated in openings 19a in ring 19 and having an eccentric socket 24a for the reception of the pins 22a carried by the dogs. The dogs are guided in 90 their inward and outward movements by suitable pins 19b stationary in the ring 19 and fitting within the slots 22b in the dogs.

The upper portion of the seat 13 of the valve body is provided with serrations for the reception of the teeth of the dogs 22.

The blow out preventer fits the drill stem 5 95 snugly, and is, therefore, engaged by the coupling 25.

26 indicates a guide for the drill stem which serves to protect the threads 27 by which the valve body may be connected to a production 100 flow pipe after the well has been drilled.

If, during drilling operations, fluid under high pressure is encountered, the blow out preventer may be clamped about the drill stem above the valve body and permitted to fall through the 105 opening 11 upon the seat 13. The drill stem is then lowered. The coupling 25 will engage the upper ring 19; the weight of the drill stem will force the upper ring 19 downwardly; and, as the ring 20 is held stationary by the seat, the 110

rubber packing ring 21 will be radially expanded into sealing engagement with the seat 13. The dogs 22 are thereupon automatically moved by the springs 23 into locking engagement with the 5 seat.

The space between the casing and drill stem is thereby sealed, and should the pressure thereafter become sufficiently great to elevate the drill stem 5, that coupling thereon immediately 10 below the coupling 25 will be moved upwardly into engagement with the lower ring 20 which will prevent ejection of the drill stem from the casing.

When it is desired to remove the blow out 15 preventer, the dog actuating device 24 (Fig. 4) is employed to move the dogs 22 into their inactive positions. The drill stem may then be elevated and the blow out preventer removed therefrom.

The apparatus shown by Figs. 4 and 5 is the 20 same as that shown by Figs. 1, 2 and 3 except that a different blow out preventer is employed to permit closure of the valve while the drill 25 stem is in the casing. This preventer is indicated at 28. It is frusto-conical in form and includes a pair of sections 29 and 30 hinged at 31; latched at 32; and having dogs 33 urged into their active positions by springs 34 and 30 movable into their inactive positions by device 24 rotatable in openings 35. Fitting in grooves 35 in its periphery are packing rings 36 to sealingly engage seat 13. It also has in its upper portion an axial recess 37 for the reception of the coupling 25 of the drill stem. The packing ring 38 is employed to seal the drill stem coupling 25 to the blow out preventer.

If, during drilling operations, a blow out is threatened, the blow out preventer 28 may be clamped about the drill stem 5 and dropped through the opening 11 upon the seat 13. The 40 drill stem may then be lowered until the coupling 25 enters the recess 37 and rests upon the packing ring 38. That portion of the drill stem above coupling 25 may then be disconnected therefrom, and the gate valve 6 may be moved 45 across the fluid passageway in the valve body upon the valve seat 8 to completely shut off the flow of fluid.

The valve is adapted for use not only with 50 drilling equipment as herein described; but also with production equipment, which latter use is disclosed in a companion application for Letters Patent.

When oil or any other fluid for which the well 55 is drilled is encountered, it is sometimes desirable to leave the drill stem in the casing rather than to remove it from the casing and insert in its place a tubing. This may readily be done with the apparatus as shown by Fig. 4, because the guide 26 may be removed and a suitable coupling 60 (not shown) put in its place to convey fluid to the conventional flow lines.

The invention is not limited to the preferred 65 embodiments shown. Various changes will occur to those skilled in the art and may be made within the scope of the following claims.

I claim:

1. The combination with a casing, a drill stem, and a blow out preventer, of a casing head valve comprising a body mounted on said casing and 70 having a longitudinal fluid passageway communicating with the interior of said casing, the upper portion of said passageway being larger than the lower portion of said passageway to form a seat for said blow out preventer; said 75 blow out preventer being movable on said drill

stem through the upper portion of said passageway into locking engagement with said seat; and a gate movable between said seat and the upper portion of said passageway to close said passageway.

2. The combination with a casing, a drill stem, and a blow out preventer, of a casing head valve comprising a body mounted on said casing, said body having a main fluid passageway extending therethrough and communicating with the interior of said casing, the upper portion of said passageway being larger than the lower portion of said passageway to form a seat for said blow out preventer, and a branch fluid passageway communicating with the lower portion of said main fluid passageway; said blow out preventer being movable on said drill stem through the upper portion of said passageway into locking engagement with said seat; and a gate movable between said seat and the upper portion of said main passageway to close said main passageway.

3. The combination with a casing, a drill stem, and a blow out preventer on said stem, of a casing head valve mounted on said casing and 100 having an axial fluid passageway extending therethrough and communicating with the interior of said casing; the upper portion of said passageway being larger than the lower portion of said passageway to form a blow out preventer 105 seat; said stem being insertable in said passageway and casing to move said blow out preventer through the upper portion of said passageway into locking engagement with said seat.

4. The combination with a casing, a drill stem, 110 and a blow out preventer on said stem, of a casing head valve mounted on said casing and having a main axial fluid passageway extending therethrough and communicating with the interior of said casing; the upper portion of said 115 passageway being larger than the lower portion of said passageway to form a blow out preventer seat; and a branch passageway communicating with said main passageway below said seat; said stem being insertable in said main passageway 120 and casing to move said blow out preventer through the upper portion of said main passageway into locking engagement with said seat.

5. The combination of a casing; a drill stem; a blow out preventer on said stem; and a casing 125 head valve comprising a body mounted on said casing and having an axial fluid passageway extending therethrough and communicating with the interior of said casing; the upper portion of said 130 passageway being larger than the lower portion of said passageway to form a blow out preventer seat; said stem being insertable in said passageway and casing to move said blow out preventer through the upper portion of said passageway into locking engagement with said seat; 135 said stem comprising sections separable adjacent said blow out preventer; said valve having a gate movable between the upper portion of said passageway and said seat to close said passageway after separation of said sections and withdrawal from said passageway of the upper of said sections.

6. The combination with a casing; a drill stem; a blow out preventer on said stem; and a casing 145 head valve comprising a body mounted on said casing and having a main axial fluid passageway extending therethrough and communicating with the interior of said casing; the upper portion of said passageway being larger than the lower portion of said passageway to form a blow 150

out preventer seat; and a branch fluid passageway communicating with said main passageway below said seat; said stem being insertable in said main passageway and casing to move said blow out preventer through the upper portion of said main passageway into locking engagement with said seat; said stem comprising sections separable adjacent said blow out preventer; said valve having a gate movable between the upper portion of said main passageway and said seat to close said main passageway after separation of said sections and withdrawal from said main passageway of the upper of said sections. 80
